GEORGE W. DOVER AND DELMAR S. DOVER, OF PROVIDENCE, RHODE ISLAND, AS
SIGNORS TO DOVERCRAFT COMPANY, INC., OF PROVIDENCE, RHODE ISLAND, A COR-
PORATION OF RHODE ISLAND.

CURTAIN HOLDER.

Application filed September 14, 1926. Serial No. 135,349.

This invention relates to a curtain holder adapted to support a plurality of curtain draperies in proper position in front of a window and so arranged that the draperies 5 may be off-set from each other both vertically and longitudinally whereby they will present a smooth appearance suitably arranged relative to each other as viewed from the interior of the room.

10 One object of the present invention is to provide a device of this character which is of simple construction and capable of being easily placed in position upon or removed from a window casing.

15 Another object of the invention is to provide an improved form of extensible curtain rod provided with novel means for establishing the desired degree of friction between the parts thereof.

20 A further object of the invention is to provide a novel form of bracket capable of being readily and easily secured to a window casing or removed therefrom, and a novel means for removably securing the curtain rods to the brackets in such a manner as to 25 suitably support the same in position to maintain the curtain draperies in extended position in front of the window.

Other objects and advantages of the invention 30 relate to various improved details of construction as will more fully appear from the detailed description to follow.

Referring to the drawings:

Fig. 1 is a front elevational view of our 35 improved structure showing the same as applied to a window casing.

Fig. 2 is a perspective view of one of the curtain rods,

Fig. 3 is a perspective view of one end 40 section of the lower curtain rod shown in Fig. 1,

Fig. 4 is a vertical sectional view taken along the line 4—4 of Fig. 2,

Fig. 5 is a perspective view of one of the 45 brackets shown in Fig. 1,

Fig. 6 is a perspective view of a modified form of bracket,

Fig. 7 is a front elevational view of a 50 slightly modified structure, a part of the window casing being broken away,

Fig. 8 is a horizontal sectional view, taken along the line 8—8 of Fig. 7,

Fig. 9 is a horizontal sectional view, taken 55 along the line 9—9 of Fig. 7, and,

Fig. 10 is a perspective view of a further modified form of bracket.

In that form of the invention illustrated in Figs. 1 to 5 of the drawings 1 designates the side and 2 the top of a window casing of conventional form to which is secured 60 brackets 3 adjacent to the opposite sides thereof. Each bracket 3 is provided with a vertical portion 4 adapted to extend downwardly and contact with the front of the window casing and a horizontal portion 5 65 adapted to overlie the top of the casing.

The vertical and horizontal portions of each bracket are integral, and a brad 6 is formed integral with the horizontal portion of the bracket and adapted to be driven into 70 the top of the casing to hold the bracket in position. It is proposed to secure the bracket to the casing solely by means of the brad 6 although if necessary a suitable opening may be provided in the vertical portion 75 of the bracket for the insertion of a screw. When the brad 6 alone is required for securing the bracket in position it will be obvious that the structure may be applied to or removed from the casing without marring 80 that portion of the casing which is exposed to view.

A plurality of arms 7 (in the present instance three in number) are struck out from the main vertical portion of each bracket, 85 the arms extending upwardly substantially parallel with the main body portion of the bracket and being spaced therefrom a suitable distance to just permit the insertion and removal of the flat end portion of each 90 curtain rod.

The two upper curtain rods shown in Fig. 1 are constructed as shown in Fig. 2 and each comprise a central sheath member 9 of channel shaped cross-section, the edges 95 thereof being inturned as shown at 10 in Fig. 4 to engage the opposite side of the end sections when the parts are in assembled position, and two end sections 11 for engagement with the brackets. The two end sections 11 are of similar construction and are each provided with a straight portion 12 for insertion into one end of the central member 9, a bead 14 being formed on one side of the straight portion 12 for engagement 100 with the channel portion of the central member to provide suitable friction for holding the members in position relative to 105

each other. The opposite ends of said end sections are inturned toward the casing and bent back to form a relatively straight portion 16 adapted for insertion between one of the arms 7 and the main body portion of the bracket, and a slot 17 is formed in the under side of the portion 16 of sufficient width to receive the base of one of the arms 7 to prevent the parts 11 from sliding relative to the member 9 when the rods are in position.

The lower curtain rod shown in Fig. 1 differs slightly in construction from the two upper rods in that while the central section 9 is the same in all, the end sections 19 are formed with that portion 20 which is adapted to engage the bracket extending outwardly from the main portion of the rod instead of being bent back upon itself as in the end sections 11. The portion 20 of each end section 19 is provided with a slot 21 of suitable width to receive the base of the lower arm 7.

While it has been found convenient in order to conserve space that the lower curtain rod be constructed as above described, yet, if desired all of the rods may be constructed after the manner of the two upper rods as shown in Fig. 2.

30 The three curtain rods as shown in Fig. 1 are off-set from each other both vertically and horizontally to permit the draperies carried thereby to hang smoothly and without interference with each other and in assembling the structure the draperies are first mounted upon each middle section 9 when the end sections 19 are inserted in the ends of the section 9 as indicated and the ends 20 are placed in position between the lower arms 7 and the bracket when the rod is lowered to bring the base of the arms 9 into the slots 21. The two upper curtain rods are then assembled in a similar manner.

45 The bracket 3 as shown in Fig. 6 is formed with a vertical portion 4 and horizontal portion 5, the vertical portion 4 being provided with arms 7, the parts being in all respects similar to that of the structure shown in Fig. 5, except that instead of being 50 provided with an integral brad, a nail or screw 22 is passed through the horizontal portion of the bracket and into the top portion of the window casing for holding the bracket in position on the casing.

55 In that form of the invention illustrated in Figs. 7, 8 and 9 the brackets 3 are made either as shown in Fig. 5, or as shown in Fig. 6, and the curtain rods each comprise a central section 9 as previously described and end sections 24 and 25. The end sections 24 of the two upper curtain rods each have a straight portion 26 provided with a bead 27 for engagement with the channel portion of the central member 9 as previously described in connection with the

structure shown in Figs. 1 to 4. The end sections 24 adjacent to the portion 26 are inturned towards the casing and bent back upon themselves to form a portion 27 which is further provided with two short bends 70 forming a depression 28 within which the vertical portion 4 of the bracket is adapted to fit when the parts are in assembled position as shown in Fig. 8. The extreme end of the portion 27 is bent up to provide a grip 30 by which the end section 24 may be adjusted in the central member 9 to bring the depression 28 into registry with the vertical portion 4 of the bracket.

The end sections of the lower curtain rod shown in Fig. 7 may be formed slightly different from those of the upper rods as is shown in Fig. 9, or they may be formed in the same way as those of the upper rods if desired. As shown in Fig. 9 the end sections are formed with a relatively straight portion 31 provided with a bead 32 for engagement with the channel portion of the central member 9, while the remaining portion of the end section is inturned towards the casing and extends outwardly therealong as indicated at 33. The portion 33 is provided with a pair of sharp bends to form a depression 34 in the portion 33, which depression receives the vertical portion 4 of the bracket when the parts are in assembled position, and is provided at the end with an upturned lug 35 to form a hand grip for adjusting the end sections relative to the central member 9 whereby the parts may be so adjusted that the vertical portions 4 of the brackets will enter the depressions 34. In the structure shown in Figs. 7 to 9 the grooves formed in the lower edges of the end sections are dispensed with as the parts are maintained in proper position when in use by means of the vertical portions of the brackets engaging the depressions in the end sections.

50 The modified form of bracket shown in Fig. 10 of the drawings is secured to the front of the window casing when that manner of attachment is found to be preferable, and is adapted for use in connection with that form of end sections shown in Figs. 1 to 4. The bracket 36 is provided with openings 37 by which it may be secured to the casing with screws or other suitable fasteners, and has a plurality of struck out portions 38 which are cut away at the sides to form narrow openings 39 in which the ends 16 and 20 of sections 11 and 19 may be inserted for supporting the curtain rods. When the ends 16 and 20 of the sections 11 and 19 are inserted in the openings 39 the grooves 17 and 21 are brought into registry with the base of the struck out portions 38 and the rods lowered to bring the bases of these struck out portions into the grooves whereby the sections of each rod are suit- 130

ably maintained in position until their removal from the brackets is desired.

This form of bracket is also adapted for use in connection with the type of rod shown in Fig. 2 as a support for towels or other articles and may be applied to a panel, wall or other plane surface.

From the above it will be seen that we have provided a simple and inexpensive form of holder wherein the curtain rods are readily positioned within or removed from the brackets and the construction of the rods and brackets are such as to properly maintain the curtain rods in suitable supporting position at all times.

What we claim is:

1. A curtain holder comprising a telescoping rod having a flat end section provided with a curved inturned portion and a straight end portion bent backwardly towards the main body portion of the rod and substantially parallel therewith, the straight end portion being provided with a slot formed in the lower side thereof, and a bracket member provided with struck out portions closed at the bottom to form horizontal openings for the reception of the

straight end portions of the end sections, the lower edge of each struck out portion of the bracket being adapted to fit within the slot 30 in the straight end portion of an end section to hold the rod against endwise movement.

2. A curtain holder comprising a telescoping rod having a flat end section provided with a curved inturned portion and an end portion bent backwardly towards the main body portion of the rod and substantially parallel therewith, the said end portion being provided with a slot formed in the lower 40 side thereof, a bracket member provided with a struck out portion for receiving the end portion of said rod, the lower edge of said struck out portion of the bracket being adapted to fit within the slot in the end portion of said rod, and each end portion having bends formed therein adjacent to the side edges of the struck out portions of the bracket to hold the rod against turning relative to the bracket.

In testimony whereof we have affixed our signatures.

GEORGE W. DOVER.
DELMAR S. DOVER.
